INSOLE AND METHOD OF MAKING
INSOLES

George H. Nichols, Quincy, and John A. Caswell, Somerville, Mass., assignors to United Shoe Machinery Corporation, Paterson, N. J., a corporation of New Jersey

Application May 14, 1934, Serial No. 725,452

5 Claims. (Cl. 36—22)

This invention relates to insoles and to methods of making insoles and is illustrated herein with reference to insoles provided with lips to which shoe uppers may be secured in lasted position either temporarily or permanently.

A number of synthetic materials have been developed in recent years for use as insoles in shoes of the type in which an upper is lasted over the bottom of an insole and an outsole secured in contact with the overlasted portion of the upper. These insole materials consist, for example, of layers of vegetable fiber such as wood pulp impregnated with and bound together by rubber in the form of latex and, while satisfactory for use in shoes of the type indicated, are not so satisfactory for use in shoes which require the insole to be channeled to form a lip to which an upper may be attached, either temporarily or permanently, for the reason that the channel formed in such material tends to become extended when stress is applied to the lip; that is, the layers of material tend to separate at the base of the lip.

Objects of this invention are to enable insoles of this character to be utilized effectively in shoes requiring a lip formed by a channeling operation, to which lip the upper is secured in lasted position. In one aspect the invention comprises an insole having a lip formed therein by a channeling operation and fastening means such as a through-and-through seam located at the base of the lip to prevent stress on the lip from causing the channel to be extended into the unchanneled portion of the sole. As illustrated, an inside channel is formed entirely around the periphery of the insole except at the heel-seat portion at a suitable distance from its edge, and a through-and-through seam is sewed through the body of the insole at the base of the channel lip so as to prevent the channel cut from extending outwardly, thus preventing the lip from being widened and the feather portion narrowed.

In another aspect the invention comprises a method of making insoles which consists in forming an insole lip by a channeling operation and sewing a through-and-through seam at the base of the lip to prevent extension of the channel cut in the unchanneled portion.

With the above and other objects in view the invention will now be described in connection with the accompanying drawing and thereafter pointed out in the appended claims.

In the drawing,

Fig. 1 is a perspective view of an insole embodying the present invention; and

Fig. 2 is a transverse sectional view of the insole on an enlarged scale taken on the line II—II of Fig. 1.

The illustrated insole comprises a thin flexible body portion 10 which, as illustrated herein, is made from an artificial leather composition consisting of wood fiber or pulp and a binding agent such, for example, as latex. The insole may, however, be composed of other materials, for example, leather or compositions of leather, fiber 10 or rubber, without departing from the spirit of the invention. The nature of the material disclosed herein is such that if the insole is split or channeled the severed portion will have a tendency, if force is applied thereto, to tear or peel away from the body portion of the insole in a layer which is substantially the same thickness throughout, similar to the manner in which one layer of a laminated strip of material will peel away from the main portion if it is separated and force is applied thereto.

As shown in Fig. 1, the heel portion of the insole 10 is preferably reinforced by a thin layer 12 of less flexible material such as fiberboard, so that the heel-seat portion of the insole will remain substantially flat while the shank and forepart are free to bend and thus adapt themselves readily to the shape of the last upon which the insole is to be mounted in the manufacture of a shoe. The layer 12 may be cemented to the heel portion of the insole or it may be secured thereto by cement and/or staples 14, as illustrated in Fig. 1, the ends of the staples being clinched inwardly against the outer face of the insole.

The insole 10 is next provided adjacent to its marginal portion with a channel 16 formed by making a split or cut in the outer face of the insole inwardly of the feather portion thereof, the split extending outwardly toward the edge 40 of the insole to approximately the inner edge of the feather. Thus there is provided around the margin of the insole a channel flap 18 which, when raised into an upwardly inclined position, as shown in Fig. 2, will serve as a rib or lip to which a shoe upper may be secured by staples or otherwise to hold the upper in lasted relation to the insole. The depth of the channel cut 16 is somewhat less than half the thickness of the insole and the width of the flap or rib 18 is illustrated as being approximately half the width of the feather portion of the insole.

Since the material which forms the rib has a tendency to split or peel away from the body portion of the insole when force is applied to the

rib, it will be obvious from Fig. 2 that, unless prevented, the rib 18 will tend to split toward the edge of the insole if a shoe upper were now secured to the rib, thereby widening the channel 5 16 and increasing the width of the rib 18. Accordingly, in order to prevent splitting or peeling of the material there is now inserted in the body portion of the insole a row of through-and-through stitches 20 which is located along the 10 base of the lip 18 at the outer edge of the channel and prevents the material from splitting when force, for example, the strain or pull of a shoe upper which has been secured in lasted relation to the lip, is exerted thereon. The through-and-through stitches 20, therefore, definitely determine 15 or fix the width of the lip 18 and prevent the lip from splitting away from the solid portion of the insole to widen the channel and increase the width of the lip.

20 While the insole 10 is illustrated herein as having an inside channel which starts inwardly of the marginal portion of the insole and extends outwardly to the feather portion thereof so that the flap or lip 18 will be raised outwardly or toward the edge of the insole, the through-and-through stitches being located outwardly of the channel at the outer side of the base of the rib, it should be understood that the channel may, without departing from the invention, be cut 25 inwardly from the edge of the insole so that the channel flap will be raised away from the marginal portion, the stitches in this case being located along the inner side of the base of the rib to prevent the material from peeling inwardly 30 toward the central portion of the insole.

An insole prepared as described above may be used in the manufacture of shoes the uppers of which are temporarily secured in lasted position to a lip while cement, by which the uppers are to 40 be permanently secured in lasted position, is setting. It may also be used in shoes in which the upper and a welt are permanently stitched to the lip to hold the upper in lasted position, as in the manufacture of Goodyear welt shoes.

45 Having described our invention, what we claim as new and desire to secure by Letters Patent of the United States is:

1. An insole having an inside channel cut therein the flap of said channel forming a single 50 integral lip of uniform thickness to which a shoe upper may be secured to hold the upper in lasted relation to the insole, and a single row of reinforcing stitches inserted along the base of the lip and coinciding with the outer edge of the 55 channel to prevent any widening of said channel.
2. An insole having inwardly of its marginal

portion a channel parallel to the inner and outer surfaces of the insole and extending outwardly toward the edges thereof, the depth of said channel being less than half the thickness of the insole and the channel flap forming a single 5 rib of uniform thickness to which a shoe upper may be secured, said insole being formed of material such that force applied to the rib tends to widen the channel by splitting of the material in a plane substantially parallel with the bottom 10 surface of the channel, and through-and-through stitches inserted along the base of the rib and at the outside edge of the channel to prevent the material adjacent to the channel from splitting 15 when force is applied to the rib.

3. That improvement in methods of making insoles which consists in cutting an inside channel in the marginal portion of an insole parallel to its inner and outer surfaces to provide a flap which will form a single rib of uniform thickness 20 to which a shoe upper may be secured, and inserting a single row of stitches through the insole at the base of the rib to prevent said rib from peeling into the unchanneled portion of the insole and thereby widening the channel when 25 force is applied to the rib.

4. That improvement in methods of making insoles which consists in forming an inside channel at the marginal portion of an insole parallel to the outer surface thereof to provide an integral 30 flap of uniform thickness which when raised into an upstanding position will serve as a single rib to which a shoe upper may be secured to hold the upper in lasted relation to the insole, said channel extending toward the edge of the insole 35 and being less in depth than half the thickness of the insole, and inserting a single row of stitches through the insole at the outer edge of the channel to reinforce the feather portion of the insole and definitely to determine the width of the rib. 40

5. An insole of uniform thickness and of material having a tendency to split under tension in planes parallel to the inner and outer surfaces of the insole, said insole having an inside channel located inwardly of the edge face of its outer 45 surface to leave a feather portion on the insole and to form an integral upper attaching lip of uniform thickness, and a single row of stitches located in said feather portion contiguous to the lip to prevent the material of the insole from 50 splitting under tension applied to the lip and thereby widening the lip and narrowing the feather portion of the insole.
